By his Attorney F. H. Gibbs

UNITED STATES PATENT OFFICE.

DONALD S. BARROWS, OF BOONTON, NEW JERSEY, ASSIGNOR TO AMERICAN CAR AND FOUNDRY COMPANY, OF ST. LOUIS, MISSOURI, A CORPORATION OF NEW JERSEY.

HOPPER-CAR-DOOR-OPERATING DEVICE.

1,199,754.

Specification of Letters Patent. Patented Oct. 3, 1916.

Application filed April 24, 1915. Serial No. 23,694.

To all whom it may concern:

Be it known that I, DONALD S. BARROWS, residing at Boonton, Morris county, New Jersey, and being a citizen of the United States, have invented certain new and useful Improvements in Hopper-Car-Door-Operating Devices, of which the following is a full, clear, and exact description, such as will enable others skilled in the art to which it applies to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a fragmentary end portion of a hopper car equipped with the invention showing the releasing arm in a locked position. Fig. 2 is a fragmentary side elevational view of a car equipped with the invention, the parts being in the position shown in Fig. 1. Fig. 3 is a vertical sectional view, the section being as it would appear if taken on line 3-3 of Fig. 1 looking in the direction indicated by the arrows, but is reversed for convenient comparison with Figs. 2 and 4. Fig. 4 is a similar view, the section being taken on line 4-4 of Fig. 1. Fig. 5 is a fragmentary detail showing a casting comprising bearings for shafts hereinafter referred to. Fig. 6 is a detail hereinafter described, and Fig. 7 is a detached detail view of the socket for the operating arm of the device. Fig. 8 is a fragmentary end portion of a hopper car equipped with the invention showing the releasing arm in an unlocked position.

The object of the invention is to provide simple, reliable and accessible means adapted to be attached to the end of a dumping car or car comprising dumping bottom doors in whole or in part, which device may be associated with means for actuating the operating shaft and co-operating therewith to secure safety in operation while the operating shaft is employed to lift the doors and which will automatically release the means for locking the shaft in position during certain movement of the releasing. While the

device is shown applied to a dumping car in which is employed a winding shaft actuated through a gear on said shaft and a pinion on a separate shaft, the device would work equally as well with the separate shaft and pinion omitted and the operating arm hereinafter referred to secured directly to or upon the winding shaft.

Referring to the parts, D indicates the winding shaft hereinbefore referred to which shaft is provided near its outer end with a non-circular portion S on which is held a ratchet wheel B and outside of said ratchet wheel is a large gear wheel a. The outer end of this shaft at r is circular as shown and is perforated so as to adapt it to receive through such perforation a large cotter pin r' employed to lock the large gear wheel and said ratchet in position on said shaft. It will be observed that said shaft extends through the opening o in an inner bearing plate w secured to the end of the car and an outer bearing plate s is also held in position on the shaft D by said cotter pin before referred to.

Mounted on the bearing sleeve 9 of plate w is a stub shaft 10 on which is mounted the bifurcated lower end portion of the releasing arm 11. This bifurcated lower end 8 of the arm 11 is of relatively large area and held between its bifurcations are two spools or thimbles 13 secured in position by suitable rivets 14, and it will be seen from an inspection of Figs. 1 and 8 that there is one of said spools at each side of the pawl 15, which pawl is pivotally mounted on the stub shaft 10 before referred to, as indicated at 16 in Fig. 1. The invention relates specifically to the co-operation of said releasing arm, said pawl and the means for operating the pawl 15 in whatever position said pawl may be placed.

In the present instance a shaft 18 extends through the bearing sleeve 19 of the plate w and said shaft is non-rotatable being locked in its bearing sleeve 19 by means of the pin 23, shown in Fig. 3, which pin extends through said shaft and through the wall of said sleeve. On the outer end of the shaft 18 is mounted the pinion 24 which pinion is provided on its outer end with a non-circular hub portion 25 on which is held

the ratchet wheel 26 so that said ratchet wheel and pinion necessarily rotate synchronously.

Intermediate the ratchet wheel 26 and the 5 teeth of the pinion 24, the hub of said pinion is provided with a circular portion 27 on which is mounted, so as to be freely rotatable, the bearing 28 for the socket handle 29 of the operating arm 30 and pivotally 10 connected at 31 to the socket handle 29 is a pawl 32 which, as will be noted in Fig. 8, is adapted to bear against and interlock with the teeth of said ratchet wheel 26 so that when the operating arm is moved 15 contra-clockwise, as indicated by the arrow in Fig. 8, the pawl 32 will bear against the ratchet wheel 26 rotating the pinion 24 in the same direction on the shaft 18 and due to the intermeshing of the pinion 24 with 20 the gear α on the winding shaft D, said winding shaft will be rotated in a clockwise direction, pinion 24 and gear α forming a power-multiplying gear train for delivering increased motive force to shaft D. 25 During this operation the releasing arm will stand in substantially the position indicated in Fig. 1 in which position one of the spools 13 will bear on the upper face of the pawl 15 and cause said pawl to support more or less of the weight of said releasing arm 11, hence automatically causing 30 the pawl to interlock with the ratchet wheel B, before referred to, while the shaft D is moving in a clockwise direction, during 35 which operation the operating arm 30 will occupy substantially the position shown in Fig. 8, or within its zone of operative movement. When the shaft D has been turned a suitable number of times to accomplish 40 the desired purpose as, for example, to lift the dumping doors of a car, the releasing arm is locked in the position shown in full lines in Fig. 1 by means of the loop 40 which is carried on the grab-iron 41, which 45 grab-iron is secured to the end plate 42 of the car shown in that figure. When it is desired to dump the load, that is, to release the winding shaft, all that is necessary is to throw off the loop 40 from its engagement 50 with the releasing arm, and the releasing arm may then be moved to the position shown in full lines in Fig. 8, whereupon the lower or left hand spool 13 will engage with the lower face of the pawl 15 55 and lift said pawl from its engagement with the ratchet wheel B, that is, will move said pawl from its position shown in dotted lines in Fig. 1 to the two positions shown in dotted lines in Fig. 8, it being understood 60 that prior to releasing the pawl 15 the operating arm is released from its engagement with the ratchet wheel 26 by throwing out of engagement the pawl 32, before referred to. When the arm 11 is moved 65 from the position shown in full lines in

Fig. 1 to the position shown in full lines in Fig. 8, it will drop by gravity to the position shown by dotted lines in Fig. 8.

What I claim is:

1. In a dumping car, a winding shaft, 70 an end wall forming a bearing for one end of said shaft, a ratchet wheel on said shaft, a pawl adapted to coöperate with said ratchet wheel, a rockable member having with said pawl a common pivot and means 75 on said rockable member at two sides of said pawl each adapted to bear thereagainst at a predetermined time.

2. In a device of the character described, 80 a rockable handle bifurcated near one end and connected across the bifurcation at two points, a pivot relatively intermediate said connected points of the bifurcation, and a pawl rockable on said pivot adapted to contact with the connection at said points. 85

3. In a device of the character described, 90 a shaft, a ratchet wheel thereon, a pawl and a rockable member provided with contact devices adapted, respectively, to maintain said pawl in engagement with said ratchet wheel through the gravitational influence of said rockable member and to disengage said pawl from said ratchet wheel by a rocking of said member.

4. In combination, 95 a shaft, a ratchet wheel rotatable therewith, a pivoted pawl, a rockable member and devices carried thereby disposed on opposite sides of said pawl and adapted respectively, to cause said pawl to engage and disengage said ratchet wheel in response to the position of said rockable member.

5. In combination, 105 a pair of shafts, a ratchet wheel on each shaft, a suitably actuated driving pawl adapted to engage one ratchet wheel and a detent pawl for the other ratchet wheel, a rockable member by which said detent pawl is movably confined and caused to, respectively, engage and disengage the last mentioned ratchet wheel and a driving connection between the first mentioned ratchet wheel and the shaft bearing the second mentioned ratchet wheel. 110

6. In combination, 115 a pair of shafts, a gear on one shaft provided with an extended hub, a ratchet wheel fixedly mounted on said hub, a suitably actuated driving pawl therefor, a rockable member provided with means adapted to engage said detent pawl on opposite sides and to move the same into and out of coöperative relation with the last mentioned ratchet wheel and a gear connection between said gear and second mentioned shaft. 120

7. In combination, 125 a pair of shafts, a gear on one shaft provided with an extended hub, a ratchet wheel and an operating lever fixedly and loosely mounted, respectively, on said hub, a driving pawl for said ratchet wheel carried by the operating lever, a gear 130

and a ratchet wheel fixed to the other shaft the former and first mentioned gear being in the same gear train, and a detent pawl adapted to be thrown into and out of coöperative relation with the last mentioned ratchet wheel.

8. In combination, a suitably actuated power multiplying gear train, a shaft adapted to be driven thereby, a ratchet wheel secured to said shaft, a detent pawl therefor and a rockable member adapted to limit the movement of said pawl and to cause it to engage and disengage said ratchet wheel.
15. 9. In combination, a shaft, means for driving the same from another point, a ratchet wheel secured to said shaft and a detent pawl and a rockable member having a common pivot said member being adapted 20 to maintain said pawl engaged with said ratchet wheel through gravity and to disengage said pawl by a predetermined actuation of said member.
10. In combination, a shaft, a gear train 25 for driving the same one of the gears having an extending hub, a ratchet wheel and an operating arm the former fixed to said hub and the latter suspended therefrom but adapted to be moved to an operative position, an actuating pawl for said ratchet

wheel mounted on said operating arm, a ratchet wheel on said shaft, a detent pawl therefor and gravity operable means for positioning and tripping the same.

11. In combination, a shaft, a gear train 35 for driving the same one of the gears having an extended hub, a ratchet wheel and an operating arm the former fixed to said hub and the latter suspended therefrom but adapted to be moved to an operative position, and an actuating pawl for said ratchet wheel mounted on said operating arm.

12. In combination, a base, a pivot and a stud shaft mounted thereon and a rotatable shaft extending through and supported by 45 said base, means for driving said rotatable shaft connecting both shafts, a ratchet wheel on the rotatable shaft and a pawl and rockable member mounted on said pivot the rockable member being adapted through 50 gravity to maintain said pawl in engagement with said ratchet wheel and movable to trip the pawl.

In witness whereof I have hereunto set 55 my hand in the presence of two witnesses.

DONALD S. BARROWS.
